UNITED STATES PATENT OFFICE.

JOHN BEERY, OF DECATUR, INDIANA.

SCHOLAR'S COMPANION.

SPECIFICATION forming part of Letters Patent No. 686,249, dated November 12, 1901.
Application filed May 20, 1901. Serial No. 61,122. (No model.)

To all whom it may concern:

Be it known that I, JOHN BEERY, a citizen of the United States, residing at Decatur, in the county of Adams and State of Indiana, have invented a new and useful Improvement in Scholars' Companions, of which the following is a specification.

The object of the invention is to provide an attachment for a school-desk or the like, having a receptacle adapted to receive pencils, penholders, erasers, rulers, &c.

The invention consists in the construction and combination of elements hereinafter specifically described and claimed.

15 The invention is illustrated in the accompanying drawings, wherein the same reference-letter is used to designate the same part in the several views, and in which—

Figure 1 is a perspective view of the attachment ready to apply to the lower surface of a desk-top. Fig. 2 is a longitudinal section on the line $x-x$, Fig. 1, looking in the direction of the arrow; and Fig. 3 is a longitudinal section of the front portion of the drawer, showing the felt lining thereof.

Referring now specifically to the drawings, A designates a drawer-guide, consisting of side pieces a , end piece a' , and a bottom a'' . Suitably secured to the bottom and sides of the 30 guide are two sheet-metal straps b b , one at either end of the drawer, having attaching-ears b' , through which screws are adapted to pass, by which the guide is secured to the under side of the top of any ordinary school-desk.

C designates a drawer constituting the receptacle for the pens, pencils, rulers, &c., of the pupil, which is preferably lined with felt or the like (indicated at d) to prevent any 40 noise which might result from the pencils shifting from one side to the other of the receptacle. The drawer is provided with the ordinary knob, screw-eye, or the like, by which it may be drawn out. On one side of this 45 drawer a series of recesses e is provided, any one of which is adapted to receive the end of a stop-pin f , suitably secured to the end of a plate-spring g , fastened to the side of the drawer-guide, said spring-actuated stop-pin 50 projecting through an aperture in the side of said guide. Preferably a staple h is provided,

which serves to guide the plate-spring in its movement, although it is not necessary to its operation and might be dispensed with.

The letter D designates a retractile coiled 55 spring suitably connected to the end pieces of the drawer-guide and drawer, respectively, which normally pulls the drawer into contact with a buffer i , secured to the bottom of the drawer-guide, and thus holds the drawer 60 closed. This buffer, as shown, consists of a block of wood, to the front portion of which a piece of felt, rubber, or the like, k , is secured; but any suitable device may be used 65 for this purpose, such as the ordinary pneumatic door-stop, constructed on the plan of a bicycle-pump.

When the desired article has been procured, the stop-pin f is released from the recess e by drawing it outward against the tendency of 70 the plate-spring g . As soon as this is done the spring D is free to act and pulls the drawer into its closed position.

The end of the drawer may be provided 75 with a piece of felt, rubber, or the like to co-operate with the buffer i to relieve any shock which may be caused by the too-violent action of the spring.

While the device is intended primarily to be attached to a desk, this is not necessary, 80 as the attaching-straps b and staple h may be omitted and the whole device made of suitable proportions, so that it may be carried in the pocket of the pupil.

It is apparent that in carrying out my invention some changes from the construction herein shown and described may be made, and I wish to have it understood that I do not limit myself to that construction, but hold myself at liberty to make such changes 90 therefrom as fairly fall within the scope of my invention.

Having described my invention, what I desire to claim and secure by Letters Patent is—

1. A scholar's companion comprising a drawer providing a receptacle for pencils, &c., a guideway therefor having a rear cross-piece, a buffer secured to the guideway in front of and removed from the rear cross-piece, a coiled retractile spring secured at one end to the rear of the drawer and at the 95 100

other to the rear cross-piece, whereby the spring holds the drawer against the buffer in its closed position.

2. A scholar's companion comprising a drawer providing a receptacle for pencils, &c., a guideway therefor having a rear cross-piece, a buffer secured to the guideway in front of and removed from, the rear cross-piece, a coiled retractile spring secured at one end to the rear of the drawer and at the other to the rear cross-piece, and means to hold the drawer in its opened position against the tension of the spring.

3. A scholar's companion comprising a drawer providing a receptacle for pencils, &c., a guideway therefor having a rear cross-piece, a buffer secured to the guideway in front of and removed from the rear cross-piece, a coiled retractile spring secured at one end to the rear of the drawer and at the other

to the rear cross-piece, and means automatically operating to lock the drawer in its opened position.

4. A scholar's companion comprising a drawer providing a receptacle for pencils, &c., a guideway therefor having a rear cross-piece, a buffer secured to the guideway in front of and removed from the rear cross-piece, a coiled retractile spring secured at one end to the rear of the drawer and at the other to the rear cross-piece, and means to hold the drawer in a plurality of forward or opened positions.

In testimony whereof I have signed this specification in the presence of two subscribing witnesses.

JOHN BEERY.
